United States Patent

Des. 238,456
Patented Jan. 13, 1976

238,456

BLOOD FILTRATION UNIT

Herman Charles Mouwen, Ventura, Calif., and Francis Martin Servas, Belle Mead, N.J., assignors to Johnson & Johnson and Purolator, Inc.

Filed May 28, 1974, Ser. No. 473,478

Term of patent 14 years

Int. Cl. D23—99; D24—02
U.S. Cl. D83—12 A

FIG. 1 is a perspective view of a blood filtration unit showing our new design;

FIG. 2 is a front view of the unit shown in FIG. 1;

FIG. 3 is a side view of the unit shown in FIG. 1;

FIG. 4 is a rear view of the unit shown in FIG. 1;

FIG. 5 is a top plan view of the unit shown in FIG. 1; and

FIG. 6 is a bottom plan view of the unit shown in FIG.

1.

We claim:

The ornamental design for a blood filtration unit, as shown.
